UNITED STATES PATENT OFFICE.

HANS O. KISE, OF HANLEY FALLS, MINNESOTA.

GRAIN-ELEVATOR.

1,087,667.

Specification of Letters Patent. Patented Feb. 17, 1914.

Application filed August 8, 1912. Serial No. 713,987.

To all whom it may concern:

Be it known that I, HANS O. KISE, a citizen of the United States, residing at Hanley Falls, in the county of Yellow Medicine and State of Minnesota, have invented certain new and useful Improvements in Grain-Elevators; and I do hereby declare the following to be a full, clear, and exact description of the invention, such as will enable others skilled in the art to which it appertains to make and use the same.

My invention has for its object to provide an improved grain elevator and, to this end, it consists of the novel devices and combinations of devices hereinafter described and defined in the claim.

The invention is illustrated in the single view of the accompanying drawing, which is a view partly in side elevation and partly in central vertical section, some parts being broken away.

For the purpose of showing the improved grain elevator in working position, a portion of a granary has been illustrated in the drawing.

Of the parts of the granary, the numeral 1 indicates a driveway therethrough having, at its intermediate portion, a pit 2, on each side of which is a plurality of bins, not shown. Within the pit 2 is mounted the improved grain elevator which is supported on a rectangular frame 4 having legs 5. On top of the frame 4 is secured an open bottom feed hopper 6 having its upper end substantially level with the driveway 1, in a position to receive grain dumped or shoveled from a wagon. A conveyer, preferably spiral, only the shaft 9 of which is shown, is provided for delivering grain from the hopper 6 to a fan casing 10 on the frame 4. Within the casing 10 is mounted a centrifugal fan, not shown, the shaft 13 of which is journaled in bearings, not shown, secured to the top of the frame 4. The conveyer shaft 9 is driven from the fan shaft 13 through a countershaft 17 journaled in bearings on the frame 4 and having secured thereto sprocket wheels 21. Sprocket chains 18 and 19 run over the sprocket wheels 21 and also, respectively, over relatively small and large

sprocket wheels 16 and 22, which are secured, respectively, to the shafts 18 and 9. The conveyer shaft 9 is journaled in a bearing 23 secured to the frame 4.

As the grain is delivered to the fan casing 10, the same is carried upward, with the blast of air from the fan, through a vertically extended stack 24. At its lower end, the stack 24 is swiveled on a base section 25 rigidly secured to the frame 4, which forms a continuation of said stack 24 directly to the delivery end of the fan casing 10. To the upper end of the stack 24 is rigidly secured a segmental hood 26 having swiveled to the lowest point thereof a delivery pipe 27 that terminates in a laterally bent delivery end. In each side of the hood 26 are formed, as shown, two dust escape ports 28, partly covered by deflecting plates. As the grain is forced out of the stack 24, the same will strike the periphery of the hood 26 and be deflected thereby to the delivery pipe 27 and a large portion of the dust carried with the grain will escape through the ports 28. From the hood 26, the grain will enter the pipe 27 and be delivered thereby into any one of the several bins of the granary, depending on the positions in which the hood 26 and pipe 27 are set.

What I claim is:—

In a device of the kind described, the combination with a stack and a support therefor, of a hood mounted on the upper end of said stack and arranged to receive therefrom, said hood having a discharge opening located below the delivery end of said stack and being movably mounted with respect to said support, to permit its discharge opening to be rotated around the axis of said stack, and a discharge pipe swiveled in the discharge opening of said hood and having a laterally extended discharge opening, substantially as described.

In testimony whereof I affix my signature in presence of two witnesses.

HANS O. KISE.
